UNITED STATES PATENT OFFICE.

GEORGE M. ASHTON, OF NIOBRARA COUNTY, WYOMING.

PUMPING JACK.

Application filed January 16, 1922. Serial No. 529,411.

To all whom it may concern:

Be it known that I, GEORGE M. ASHTON, a citizen of the United States, and a resident of Niobrara County, State of Wyoming, 5 have invented certain new and useful Improvements Relating to Pumping Jacks, of which the following is a specification.

In the natural-oil industry a large number of wells, for instance ten or even fifty, 10 are pumped from a single station or power plant by means of cables extending from the plant to the wells respectively, there being sometimes cable extensions from one well to another, the power plant being such as to 15 provide an intermittent pull and release upon each of the cables. At each well a device commonly called a jack is installed, the jack having for its function the conversion of the horizontal pull of the cable into a 20 vertical pull adapted to lift the pumping rod, the weight of the rod causing it to fall between the intermittent pulls. The use of a single power plant effects, of course, a very great saving in production cost, and it is 25 only in isolated instances, as where a particular well is too far from the general plant, that pumping is done by the mechanism including the walking beam, and the power plant, used for drilling the well. In such 30 instances the plunger rod is connected with the end of the walking beam directly over the well, and the engine adjacent to the derrick, and individual to that plant, is kept in operation so long as pumping is done.

When such a jack as I have hereinabove referred to is installed at the well to be pumped it is placed on the flooring of the derrick immediately adjacent to the well, and objectionably occupies considerable 40 space at the very center of pumping operations. From time to time the well must be cleaned of the heavy, pasty petroleum compound which collects therein, and at such time the jack must be removed, entailing loss 45 of time and other expense. Such a location of the jack is objectionable on various other grounds, but, so far as I know, that is the only arrangement thus far suggested. So far as I know, too, the jacks thus far suggested deliver to the pumping rod a relatively quick and sudden pull on each work stroke, providing great strain, wear and tear, and frequently breakage of parts.

The chief objects of the present improvements is to provide an arrangement of a 55 jack with the walking beam of the usual

well-drilling equipment whereby such objections as those hereinabove mentioned may be overcome; and to provide a simple, highly effective, strong, durable and relatively cheap form of jack, one which occupies relatively small space, and one which may advantageously be used for operating the usual walking beam, and thus to provide many advantages, as indicated, over prior 60 devices of this general class.

In the accompanying drawings, which form a part of this specification, Figure 1 is an elevation showing fragments of ordinary well-drilling equipment with the present 70 improvements operatively associated therewith; Fig. 2 is a fragmentary end elevation of certain parts shown in Fig. 1; Fig. 3 is an elevation of my improved jack as viewed from left to right in Fig. 2; Fig. 4 is a top 75 plan of the device of Fig. 3; Fig. 5 is a view at right angles to the view shown in Fig. 3; Fig. 6 is a medial vertical section through the device of Fig. 5; Fig. 7 is a top plan of the device with the top plate removed; and 80 Fig. 8 is an enlarged section showing a connection at the lower end of the pitman shown in Fig. 1.

The several structures shown in Figure 1, with the exception of my improved jack and 85 its connection and arrangement with the walking beam and pumping rod, may be considered as of well known and ordinary form. For drilling the well the walking beam 15 is operated by the pitman 16 driven 90 by the crank 17 on the shaft 18 having a wheel 19 driven by the belt 20 which leads to the engine, say twenty to forty feet away. For drilling operations the cable leading to 95 the drill is connected to the front end of the walking beam. Figure 1 shows the pump rod 23 operatively connected to the front end of the walking beam whereby the normal up-and-down rocking movement of the walking beam will lift the rod 23, its weight 100 drawing it down when the lifting pressure is withdrawn.

According to these improvements a jack is caused to operate the walking beam, and, in the form shown, the jack is connected directly with the pitman 16.

My improved jack, in its preferred embodiment, includes a base or main support comprising a ring 25 adapted to rest upon a suitable support, as flooring, and to be 110 secured thereto as by bolts 26, a central elevated part 27 smoothed off horizontally on

top to provide a bearing surface, and radial vanes 28 and a bearing-support part 29 connecting the central part 27 with the ring. This base is preferably in the form of an 5 iron casting, and in practice may appropriately be thirty to thirty six inches across, or of other shapes and proportions. It is desirable to make the device strong throughout and the form shown lends itself well to 10 the requirements of strength.

A bearing stud 30 is secured vertically in the middle part 27 of the support in any approved way. On this stud is mounted for 15 horizontal rocking movement a disc-like plate 31 having hub-like extensions below and above to provide thickness at the bearing, a nut 32 and cotter pin 33 maintaining the plate 31 in its operative position. A circular downwardly-directed rack 34 is carried coaxially upon the plate 31, and, since 20 the plate 31 may also be a casting, this rack may well be integral with it.

A radially-arranged shaft 36 is carried by the support 29 formed to provide bearings, 25 as well indicated in Figures 6 and 7, these bearings having caps 37 and 38 respectively for holding the shaft in place. A gear 40 is rigidly secured upon the shaft 36, as by a pin, set-screw or key and is held between the 30 shaft bearings. When the plate 31 is in its operative position the gear 40 is in mesh with the rack 34.

The outer end of the shaft 36 is made square at 42 and a nut 43 holds the crank 35 arm 44 upon the shaft. This crank arm is provided with the plurality of holes 49 at different distances from the shaft 36, as shown in Fig. 6, to provide for a longer or shorter stroke as may be desired, and a pair 40 of connecting rods or links 45 are secured upon the crank arm 44 by a crank pin 46, shown in the form of a simple bolt passing through one of the holes mentioned. The flat rods or links 45 extend upward and are 45 connected on opposite sides of the lower end of the pitman 16 by a bolt 47 (Fig. 8) passing through a bushing 50, the bushing being provided to fill up the excess of space of the large hole at the lower end of such pit- 50 man adapted to receive the crank pin of the driving crank 17.

Around the periphery of the plate 31 I provide a plurality of holes 53 adapted to receive a bolt 54 of a clevis 55 to which is 55 connected the pull member 56 shown as a cable which is to be understood as leading to the distant central power plant. The connection with the cable 56 can thus be made at a great many places around the 60 edge of the plate 31 whereby the desired pulling force may be had from any one of a plurality of widely divergent substantially horizontal directions determined by the relative locations of the power plant and the 65 well.

The top plate 31 is simply a specialized form of lever, the effective end of which is at any particular one of the holes 53 which may accommodate the clevis bolt 54. Being made plate-like it avoids the necessity of adjustments of the lever to adapt the device for use in connection with the cable coming from any particular substantially horizontal direction. It also forms a protective cover for the gears, provides a useful table for various purposes when the device is not in use, and gives to the device as a whole an advantageous form. 70 75

In installing my improved jack it is preferably located at a place adjacent to an area 80 substantially beneath the rear end of the pitman 16 and with the shaft 36 directed at right angles to the up-and-down movement of the pitman and with its crank arm 44 positioned to rock in planes parallel with 85 the up-and-down and forward-and-back motion of the pitman. The pumping stroke is normally from sixteen to twenty inches long, which is not nearly that of the stroke used for drilling, so that a relatively small movement of the walking beam 15 takes place. 90

In connecting the jack with the pitman initially the pump rod 23 is adjusted to its desired lowermost position with the rear end of the walking beam 15 slightly raised 95 from the horizontal, say eight to ten inches, and thereupon the links 45 are connected to the pitman with the jack crank arm 44 in a vertical position. Thereupon the pullable 56 is connected approximately tangentially to the plate 31 at one side or the other of its vertical axis of movement as may be preferred. 100

When the periodical pulling impulses are made upon the cable the plate or lever 31 105 is correspondingly moved on its axis, the circular gear or rack 34 transmits motion to the gear 40 and the crank arm 44 is moved arcuately downward, drawing the walking beam down and raising the pump rod 23. 110 Upon subsidence of the pull the weight of the pump rod restores the parts to their first relative positions, and thus the pumping is done continuously so long as the intermittent pulls are made upon the cable. 115

The rack 34 is made in circular form for various reasons. This construction avoids the necessity of any adjustment when the parts are assembled. It also provides a large number of teeth on the rack which may 120 be used throughout the life of the device, although only a relatively small number are being used at a particular time; and it thus also provides for a continuance of the device in use should one tooth of the rack become broken or even should various teeth break here and there, it being only necessary that a sufficient number remain good. It provides also for an equalized wear upon 125 the teeth, both of the rack and of the gear, 130

since in assembling the device from time to time the crank 44 may be applied to the shaft 36 with the teeth of the lever plate 31 in various relative operative positions with respect to particular teeth of the gear 40. The gear 40 is an easily replaceable element should a breakage of any of its teeth occur. Since, however, all of these parts are susceptible of being made quite strong, the danger from breakage is reduced to a minimum and the construction shown results in a device which will have unusual life and efficiency in service and thus overcome a serious objection to present-day forms of jacks.

The shaft-supporting part 29 of the main support or base is preferably formed with a pocket at 60 adapted to contain grease for lubricating the gear members, and the bearings of the shaft also through the spreading of the grease.

An important feature of this system of pumping wells resides in the fact that the down pull upon the rear end of the walking beam may begin with an exceedingly small amount of movement, thus relieving all of the parts from the violent strains due to a sudden application of pulling force. When it is considered that the weight of the pumping rod alone may be thousands of pounds the advantage of such a slow and gradually-increasing application of lifting force will be clear. Furthermore, the long walking beam provides a very desirable and advantageous up-and-down movement for pumping in that the arc of its swing, for the relatively short stroke employed departs but slightly from a tangent. With the regular drilling walking beam or any other distantly-overhead walking beam used as herein suggested the floor of the derrick about the well is always clear for many desired operations. It is pointed out, also, that where a jack is applied near the well on the derrick floor, it must be adjusted carefully to place each time it is reset after being taken away, and that such disconnection and replacement will ordinarily consume several hours by a crew of men, the pumping being necessarily delayed by that much time, whereas, according to these improvements the necessary disconnections and connections can be made in less than five minutes.

I contemplate as included in the present invention various departures from what is specifically herein illustrated and described, as indicated in the appended claims.

I claim:

1. In a system for pumping oil from a well, the combination of a relatively long walking beam substantially horizontally mounted for vertical rocking movements and having its front end directly over the well to be pumped, a pull member having an in-

termittent substantially horizontal pulling motion and extending to a place in the vicinity of the area below the rear end of the walking beam, and means for pulling the rear end of the walking beam downward with an intermittent movement, said pulling means including a lever to which the pull member may be secured for operative effect when the pull member extends to said lever from any one of a plurality of widely divergent substantially horizontal directions.

2. In a system for pumping oil from a well, the combination of a relatively long walking beam substantially horizontally mounted for vertical rocking movements and having its front end directly over the well to be pumped, a pull member having an intermittent substantially horizontal pulling motion and extending to a place in the vicinity of the area below the rear end of the walking beam, a rocking arm mounted to rock with an upward and downward movement adjacent to a place below the rear end portion of the walking beam, connection means between said rocking arm and the rear end portion of the walking beam, and means intermediate said rocking arm and said pull member for rocking the rocking arm downward to move the rear end of the walking beam downward when a pull is made by said pull member, said last-mentioned means including a lever member adapted to be moved by pulling strains by said pull member to operate the device when said pull member extends to the lever member in any one of a plurality of widely divergent substantially horizontal directions.

3. In a pumping jack, the combination of a base, a lever member mounted for rocking movements thereon on a substantially vertical axis, means associated with said lever member adapting it to be moved by pulling strains from a pull member extending to it from any one of a plurality of widely divergent substantially horizontal directions, a horizontally-disposed shaft carried by said base for rocking movements, a gear member on said shaft, said lever member having a rack meshing with said gear, and a crank arm carried by said shaft.

4. In a pumping jack, the combination of a base, a lever member mounted for rocking movements thereon on a substantially vertical axis, means associated with said lever member adapting it to be moved by pulling strains from a pull member extending to it from any one of a plurality of widely divergent substantially horizontal directions, a circular rack carried by said lever concentric with the axis of lever movement, a gear mounted to rock on a substantially horizontal axis and in mesh with said rack, and means including a crank arm operatively connected with said gear for giving a downward pull by the crank arm when said lever

is rocked by a substantially horizontal pull.

5. In a pumping jack, the combination of a base having a bearing member substantially vertically upstanding therefrom, a 5 wheel-like lever member mounted on said bearing member, the lever member having means around its peripheral portions for connecting a pull member thereto at various places thereon, a rack in arcuate form carried by said lever member, a gear meshing with said rack and mounted for rocking movements, and means including a crank arm mounted for downward pulling movements operatively connected to said gear, 10 the arrangement being such that a substantially horizontal pull upon said lever member will produce a down pull movement by said crank arm.

6. In a pumping jack, the combination of 20 a base, a substantially flat plate-like lever member mounted thereon for rocking movements in a substantially horizontal plane, an arcuate rack carried on the underside of said lever member, a gear mounted upon 25 the base on a substantially horizontal axis with the gear in mesh with said rack, and a crank arm positioned for downward pulling movement operatively connected to said gear.

30 7. The combination of a walking beam, a substantially vertically-disposed pitman connected at one end thereof, a crank arm mounted to move with a pulling motion and substantially in line with the pitman, a link

connection between said crank arm and the 35 lower end of said pitman, a lever mounted to move with rocking motions in a substantially horizontal plane, and means operative between said lever and said crank arm for converting a horizontal pull upon the 40 lever into a down pull upon said crank arm.

8. In a jack of the character described, the combination of a lever mounted to rock in a substantially horizontal plane, a crank arm mounted to rock in a substantially vertical plane, and means including gearing 45 operatively associated with the lever and crank arm for converting a horizontal movement of the lever into a vertical movement of the crank arm.

9. In a pumping jack, the combination of means adapted to be connected with a walking beam of the character described for pulling one end of such walking beam downward to cooperate in producing an up-and-down movement of such end of the walking beam, a lever member adapted to be connected to a pull member and to be operated thereby when said pull member extends to said lever member from any one of a plurality of widely divergent substantially horizontal directions, and means intermediate the lever member and said first-mentioned means for converting such substantially horizontal pulls upon the lever member into 60 downwardly-directed pulls by said first-mentioned means.

GEORGE M. ASHTON.
